EX

ESIGN.

U. S. GROSJEAN.
SPOON, FORK, OR KNIFE HANDLE.

No. 15,716.

Patented Jan. 13, 1885.

UNITED STATES PATENT OFFICE.

CHARLES T. GROSJEAN, OF NEW YORK, N. Y., ASSIGNOR TO TIFFANY & CO.,
OF SAME PLACE.

DESIGN FOR A SPOON, FORK, OR KNIFE HANDLE.

SPECIFICATION forming part of Design No. 15,716, dated January 13, 1885.

Application filed October 14, 1884. Term of patent 14 years.

To all whom it may concern:

Be it known that I, CHARLES T. GROSJEAN, a citizen of the United States, residing in the city, county, and State of New York, have 5 invented and produced a new and original Design for a Spoon, Fork, or Knife Handle, of which the following is a specification; reference being had to the accompanying drawings, forming part thereof.

10 The general form of the handle of the spoon, fork, or knife is an oval, narrowing down at the shank and thence to its connection with the bowl, prongs, or blade. On the shank, in relief, are five flutes or reeds—three wide, and 15 two, at the edges, narrow. These lines terminate in rounded ends at a point where the shank widens into the head. The oval head of the spoon or fork is flatly rounded or convex on the front and back. The reverse sur-

20 face has in place of the raised reeds at the shank four incised lines or depressions its whole length. In the case of the knife-handle both sides of the handle contain the flutes or reeds.

25 In the drawings, Figure 1 is a view of the front surface of a spoon on the handle of which is placed my design. Fig. 2 is a view of the reverse side thereof. Fig. 3 is a view of the front surface of a fork on the handle

of which is placed my design. Fig. 4 is a 30 view of the reverse side of the fork. Fig. 5 is a side view of a knife on the handle of which is placed my design.

a is a flatly-rounded or convex plain oval head. *b b b* are three wide flutes on the shank. 35 *c c* are two narrower flutes, one on each side of the wider ones. *d d* are the rounded ends or points where the flutes terminate in the plain oval head of the handle. *e e, &c.*, are incised lines in the shank of the reverse surface thereof and running the entire length of the shank. 40

I claim—

1. In a design for a spoon, fork, or knife handle, consisting of a flatly-rounded or convex plain oval head, *a*, and flutes *b b b*, extending the entire length of the shank, as shown and described. 45

2. The design of spoon or fork handle, consisting of a rounded or convex head, *a*, flutes *b b*, 50 extending the entire length of the shank, and lines *e e* on the shank on the reverse surface, as shown and described.

CHARLES T. GROSJEAN.
